United States Patent Office.

JOHN T. DUFF, OF PITTSBURG, ASSIGNOR TO HIMSELF, JOHN F. GREER, OF SAME PLACE, AND DAVID H. CHAMBERS, OF BIRMINGHAM, PENNSYLVANIA.

Design No. 4,877, dated May 9, 1871.

DESIGN FOR A CHILD'S TOY.

The Schedule referred to in these Letters Patent and making part of the same.

To all whom it may concern:

Be it known that I, JOHN T. DUFF, of Pittsburgh, in the county of Allegheny and State of Pennsylvania, have invented or produced a new Design for Children's Toy, known as "Pin-wheel," and I do hereby declare that the following is a description thereof.

In the accompanying drawing, which forms part of my specification—

A represents a star, which is attached to a handle, e.
B are pin-wheels, which are pivoted to the star A.

C are flags, the staffs D of which are secured to the star A.

What I claim as of my invention is—

The design for child's toy, known as "pin-wheel," shown and described in the accompanying drawing.

JOHN T. DUFF.
